INVENTOR.

Maschil D. Converse.

UNITED STATES PATENT OFFICE.

MASCHIL D. CONVERSE, OF NEW YORK, N. Y.

PIVOTAL RIVET AND RIVETING.

SPECIFICATION forming part of Letters Patent No. 460,952, dated October 13, 1891.

Application filed January 30, 1891. Serial No. 379,658. (No model.)

To all whom it may concern:

Be it known that I, MASCHIL D. CONVERSE, a citizen of the United States, residing in the city, county, and State of New York, have 5 invented new and useful Improvements in Pivotal Rivets and Riveting, of which the following is a specification.

My invention relates more especially to pivotal rivets for tools and other articles in 10 which it is desirable to have a well-made good-fitting pivot and nicely-finished heads, as in nail-extractors, pliers, tongs, scissors, &c.; and my invention consists in the peculiar construction of the rivet and the washers or 15 parts to be united by it, whereby economy of cost is also insured, as will fully be shown hereinafter.

Referring to the accompanying drawings, Figure 1 is a sectional view of my invention 20 ready for application, with tools in place to set the same. Fig. 2 is also a sectional view of my invention after it has been applied, showing also how it has been set and secured in place. Figs. 3 and 4 represent modifications of my invention, hereinafter referred to.

Like letters indicate corresponding parts throughout the several figures.

A is the pivotal rivet, entered through the axial holes in the parts B C, which it is to 30 bind.

b and b' are bosses or hubs surrounding the pivot seat or hole on the outer opposite sides.

c and c' are the ends of the rivet finished. 35 a and a' represent a reduced portion of the rivet at each end, forming a neck and shoulder under the heads.

E and E' are cup-dies having each a cavity e and e'. These I have introduced to show 40 the manner of setting the rivet and securing it in place, to which reference is made herein-after.

The construction, application, and operation of my invention are as follows: When the 45 parts to be bound B C are of malleable or ductile metal, in their construction or forging hubs or bosses b b' are formed upon them at the point where the hole for the pivotal rivet is to be bored, of such size that after 50 the hole is bored there will be a more or less thin rim at the outer end of these hubs all round. Now a pivotal rivet is cut from a straight rod and finished with any form of head externally, but with a neck and shoul-

der formed at each end, of the general shape 55 shown in the drawings at a and a', by reducing the diameter of the rod at these points. As will be seen, the flare or flange of the head of the rivet by this construction is no larger than the diameter of the body or shank 60 of the rivet. The rivet is now entered to the position shown by Fig. 1, and two cup-dies E and E', of suitable form, are brought to bear upon the rims of the hubs b and b', and then while one of the dies is held rigidly 65 the other is struck by a hammer or otherwise forced forward toward the former, causing the rims of these hubs b b' to be crushed and compressed inwardly all round under the shoulders and into the necks of the rivet at 70 a a', firmly setting the metal and embracing the pivot and uniting the parts B and C, the cavities e e' in the cup-dies being deep enough to leave the previously-finished heads of the rivet unmarred.

It will be clear that the form of construction shown in Fig. 3 as a modification, wherein the pivotal rivet is cast or forged solid on one of the parts bound, might be adopted in some cases as an economical expedient and 80 without departing from the spirit of my invention, and that where the parts to be bound are of hard or non-ductile metal, washers made of malleable metal, of substantially the form shown in Fig. 4, as a modification, could 85 also be used without departing from the spirit of my invention.

Having described my invention, what I claim as new, and desire to secure by Letters 90 Patent, is—

1. The herein-described riveting system, consisting of a rivet having a neck and shoulder at its ends, in combination with bosses upon the sides of the parts it is to bind, substantially as and for the purposes shown and 95 described.

2. The herein-described riveting system, consisting of a rivet having a neck and shoulder at its ends, in combination with malleable-metal bosses upon the sides of the parts it is to 100 bind, constructed, applied, and to operate substantially as and for the purposes shown and described.

MASCHIL D. CONVERSE.
